US0D1089194S

(12) **United States Design Patent** (10) Patent No.: **US D1,089,194 S**
(45) Date of Patent: ** Aug. 19, 2025

(54) **ACCESS CONTROL DEVICE**

(71) Applicant: **Amazon Technologies, Inc.**, Seattle, WA (US)

(72) Inventors: **Anubhav Khanna**, Seattle, WA (US); **Robi Thomas**, Round Rock, TX (US); **Gerald J. Nievera**, Las Vegas, NV (US); **Kaushik Mani**, Sunnyvale, CA (US); **Mateusz Niewiadomski**, Lodz (PL); **Alejo Aguilar**, Las Vegas, NV (US); **Wen-Yo Lu**, Pasadena, CA (US); **Jon-Christopher Parkman**, Lake Villa, IL (US); **Cheng Kang Chen**, New Taipei (TW); **Darsheen Dineshbhai Daulet**, Ahmedabad (IN); **Robert Bernacki**, Irvine, CA (US)

(73) Assignee: **Amazon Technologies, Inc.**, Seattle, WA (US)

(**) Term: **15 Years**

(21) Appl. No.: **29/948,941**

(22) Filed: **Jun. 24, 2024**

CLAIM

The ornamental design for an access control device, as shown and described.

DESCRIPTION

FIG. 1 is a top, front, right-side perspective view of an access control device;

FIG. 2 is a bottom, front, left-side perspective view thereof;

FIG. 3 is a bottom, back, right-side perspective view thereof;

FIG. 4 is a front view thereof;

FIG. 5 is a back view thereof;

FIG. 6 is a right-side view thereof;

FIG. 7 is a left-side view thereof;

FIG. 8 is a top view thereof; and,

FIG. 9 is a bottom view thereof.

The dashed broken lines depict portions of the access control device that form no part of the claimed design. The dot-dashed broken lines represent boundaries of the claimed design and form no part of the claimed design.

1 Claim, 9 Drawing Sheets
